RADIATOR CLEANING APPARATUS

David Jesse Logan, Taylorsville, N. C., assignor of ten per cent to John Ray Jennings and ten per cent to Abner C. Payne, both of Taylorsville, N. C.

Application December 10, 1951, Serial No. 260,868

8 Claims. (Cl. 134—105)

1

This invention relates to a device for cleaning out radiators. In the art of cleaning out radiators, such as automobile radiators and the like, which are manufactured with a plurality of fins in a honeycomb arrangement and which frequently become clogged or stopped up or corroded from scale rust and the like and which must be boiled and cleaned out for proper operation, many difficulties have been encountered in cleaning the radiators properly. Heretofore, a radiator has usually been placed in a tank of boiling chemical solution and it has been necessary to leave the radiator in this tank for a period of several hours in order for the solution to penetrate every part of the radiator and to complete a thorough cleansing process. Frequently, this boiling out operation has failed to do a complete job of cleaning the radiator and the long time required to clean a radiator has made this method extremely unsatisfactory.

It is, therefore, an object of this invention to provide apparatus for cleaning radiators and the like wherein the radiator may be lowered into a vat of solution and said apparatus being designed to oscillate said radiator back and forth through the solution to cause circulation of the solution through the radiator and said apparatus also being provided with vibrating means for vibrating the radiator while positioned within the solution to further increase the efficiency of the action of the solution on the radiator.

It is another object of this invention to provide a tank adapted to contain chemical solution for cleaning out radiators, said tank being provided with a pair of upstanding beams, a removable swing rotatably mounted in said upstanding beams and having a platform on the lower end thereof adapted to be positioned within the confines of said tank, said platform having means thereon for securing a radiator to be cleaned thereto. Means are also provided for oscillating said swing to move the radiator on the lower end thereof back and forth through the solution and said apparatus also has means for vibrating the swing and the radiator thereon to provide more rapid and efficient cleaning of the radiator.

By means of this apparatus, a radiator can be cleaned thoroughly in a much shorter period of time than has heretofore been necessary and the cleaning is more thorough and the action of the chemicals on the radiator parts are more thorough due to the oscillating of the radiator in combination with the vibration thereof.

Some of the objects of the invention having

2

been stated, other objects will appear as the description proceeds when taken in connection with the accompanying drawings, in which—

Figure 1 is an elevation of the apparatus with parts broken away for purposes of clarity;

Figure 2 is a fragmentary top plan view of the radiator cleaning apparatus showing a radiator therein;

Figure 3 is an enlarged fragmentary isometric view of the upper portion of Figure 1 showing the vibrating means for the swing;

Figure 4 is a side elevation on a reduced scale looking at the left-hand side of Figure 1 with parts thereof broken away for purposes of clarity;

Figure 5 is an enlarged side elevation of the driving means for oscillating the swing looking along the line 5—5 in Figure 1;

Figure 6 is a view similar to Figure 3 but showing a modified form of means for vibrating the swing.

Referring more specifically to the drawings, the numeral 10 broadly indicates a tank which is illustrated as being circular in plan but which may be of any desired configuration and the tank 10 is provided with a bottom 11. The center portion of the bottom 11 is cut away and is provided with a sump 12. A drain 13 leads from the lower portion of the sump 12. A sludge collecting pan 14 is removably positioned within the sump 12 for collecting sludge and to prevent the same from clogging up the drain 13. The tank 10 is suitably supported by a plurality of legs 15. The tank 10 is adapted to contain solution such as a chemical boil-out solution, the upper level of which is indicated at S, which solution preferably contains chemicals adapted to act on the radiators to be treated for loosening the rust sludge therein and assisting in the cleaning process. Ordinarily, the solution S is heated and suitable means may be provided for heating the solution S within the tank 10 such as a steam coil 20 positioned within the tank 10 and having a pipe 21 leading to a source of steam or hot water or other heating medium, not shown. The pipe 21 preferably has thermostatic means, not shown, associated therewith for controlling the temperature in the interior of the tank 10 in a well known and conventional manner.

Secured to opposite sides of the tank 10, as by welding, are the lower ends of vertical beams 22 and 23, respectively. The beams 22 and 23 extend upwardly from the tank 10 and converge inwardly and are provided with vertically extending bifurcated portions 24 and 25, respectively, at

the upper ends thereof. The bifurcated portions 24 and 25 and associated parts are identical and like reference characters will apply. Each of the bifurcated portions 24 and 25 has a pin 26 on the lower portion of the slot thereof on which is mounted a compression spring 27 having a pin 28 of a bushing 29 positioned on the upper end thereof. Each of the bushings 29 is provided with a centrally disposed bearing slot 30 in which the opposite ends of a shaft 31 are rotatably mounted. The bushings 30 are preferably of bronze or other suitable bearing material.

The shaft 31 is fixedly secured to and spans the distance between the downwardly depending arms 32 and 33 of an inverted U-shaped swing member broadly designated at 34 and having an upper or web portion 35. Suitable spacing or bearing blocks 40 are secured on the outer surfaces of the upper portions of the arms 32 and 33 of the U-shaped member 34 and the blocks 40 are penetrated by the shaft 31 and it will be observed that the ends of the shaft 31 extend substantially beyond the blocks 40 on each side of the U-shaped member 34. The web 35 of the U-shaped member 34 is provided with a bracing member or handle portion 41 having an opening 42 therein adapted to receive means such as the hook 43 of a suitable hoist, not shown, for lifting the U-shaped swing member 34 and parts associated therewith.

The lower ends of the depending arms 32 and 33 of the U-shaped member 34 are fixedly secured as by welding to the opposite upper surfaces of a rectangular frame member or platform 45. The rectangular frame member 45 is open in the center as at 46 and suitable bracing plates or gussets 47 are secured to the frame 45 and to the depending arms 32 and 33 for strengthening the same. The frame 45 is provided with a pair of bolts 50 adjacent each corner thereof, which bolts 50 are fixedly secured to the frame 45 as by welding and which are preferably made of brass or other non-corrosive material. Wooden blocks 51 are positioned on the upper surface of the frame 45 and extend from side to side at the front and rear of the frame and are penetrated by the bolts 50.

A radiator such as indicated at R may thus be positioned on the frame 45 with the lower surface of the radiator resting upon the upper surface of the blocks 51. Suitable spanner members 52 having bores in the opposite ends thereof may be positioned over the radiator R with the bolts 50 extending through the bores therein and the spanner members 52 may be secured in position as by wing nuts 53 to thus secure the radiator R to the frame or platform 45. The spanner members 52 should be of wood or non-metallic and non-corrosive construction due to the fact that the action of the chemicals on the radiator has an adverse effect on any metal members in contact with the radiator.

It should be noted that each of the bolts 50 should be of sufficient height to permit a plurality of radiators R to be disposed on the platform 45 of the swing. A number of radiators could be positioned in superposed relation, each being separated by wooden spanner pieces similar to the members 52.

It is thus seen that there is provided a vat or tank with upstanding beams and an inverted U-shaped swing member 34 which may be termed a swing and which has a platform on the lower end thereof adapted to receive a radiator and

due to the bushings 29, this swing 34 may be swung about a horizontal axis on the shaft 31.

It will also be noted that the entire swing 34 may be removed from the bearings 29 by means of a chain hoist 48 or other suitable means. Now, with a radiator secured on the platform 45 of the swing 34, as heretofore indicated, the swing is moved into position with the platform 45 disposed within the confines of the tank 10 and the vat 10 is filled with a suitable solution such as the solution S. It is desirable to agitate the solution S to insure circulation and penetration of the solution throughout every part of the radiator. To assist this agitation, it is preferable that the solution be heated such as by the steam pipe 20.

Means are provided for oscillating the swing 34 back and forth about the shaft 31. Such means comprise a motor support stand 60 suitably secured as by welding to the outer surface of the upstanding arm 23 and braced as by a gusset 61.

Referring to Figures 1 and 2, it will be observed that the motor support plate 60 extends outwardly and rearwardly of the arm 23 and has a motor 62 suitably secured thereto as by bolts 63. The motor 62 has wires 64 extending therefrom to a suitable source of electrical energy, not shown. A pulley 65 is mounted on the drive shaft of the motor 62 and is connected by means of a belt 66 to a pulley 67 on the input side of a speed reduction unit 68. The speed reduction unit 68 has an output shaft 70 with a disc 71 fixedly mounted thereon. The disc 71 has one end of a link 72 rotatably mounted thereon in off center relation as at 73.

The link 72 extends forwardly and the forward or right-hand end thereof in Figure 5 is enlarged and has a slot 74 therein. The depending arm 33 of the inverted U-shaped member 34 is provided with a pin 75 which may be in the form of a bolt extending through the arm 33 and suitably affixed thereto as by welding. The enlarged end of the link 72 having a slot 74 therein is adapted to be positioned adjacent the pin 75 so that the link 72 will fit over the pin 75 with the pin 75 being positioned in the slot 74. With the link 72 in this position, it will be observed that upon rotation of the disc 71 by the motor 62 oscillation or to and fro movement will be imparted to the inverted U-shaped swing 34 to oscillate the same back and forth in the solution S.

In addition to the oscillation of the radiator 55 through the solution S, it is desirable to impart additional motion to the radiator for more effective action of the solution S thereon. To this end, there is provided vibrating means comprising a transverse plate or shelf 80 positioned intermediate the upper and lower ends of the depending arms 32 and 33 of the inverted U-shaped member 34 spanning the distance therebetween. The opposite ends of the shelf 80 are welded to the arms 32 and 33 and suitable gussets 81 and 82 are secured at the juncture of the shelf 80 with the arms 32 and 33.

The shelf or platform thus formed is provided with an inverted U-shaped housing 83 having horizontal flange portions 84 suitably secured to the shelf 80 as by bolts 85. The inverted U-shaped housing 83 has bearings 86 mounted in the vertical walls thereof in which the opposite ends of a shaft 87 are rotatably mounted. The shaft 87 has an off-center weight member 88 fixed thereon. The weight member 88 has a flat

surface 90 to cause the same to be out of balance.

One end of the shaft 87 has a pulley 91 thereon having a belt 92 positioned thereabout and extending upwardly to a pulley 93 on the drive shaft 94 of a motor 95. The motor 95 is suitably secured to the upper or horizontal extending portion of the inverted U-shaped housing 83 as by bolts 96. Wires 97 lead from the motor 95 to a suitable source of electrical energy, not shown, for driving the same. It will thus be observed that when the motor 95 is driven, rotation will be imparted to the shaft 87 and due to the unbalanced position of the weight member 88, vibration will be set up which will be sufficient to vibrate the shelf and the entire swing unit 34 to thus provide additional agitation of the radiator R within the solution S.

Now referring to Figure 6, there will be observed a modified form of vibrating means in which the motor is provided with off-center weight members on the drive shaft thereof to unbalance the same and set up the vibration and the inverted U-shaped housing 83 is eliminated. In this form of the invention, like reference characters will apply to like parts. It will thus be observed that on the shelf 80, a motor 100 is secured as by bolts 101. The motor 100 has a drive shaft 102 extending from each end thereof and the drive shaft 102 is provided with a weight member 103 secured on each end thereof as by set screws 105. The weight members 103 have flat surfaces 104. The flat surfaces 104 cause the weight members 103 to be unbalanced and as the shaft 102 rotates, vibration will be set up in the motor 100 and this vibration will be imparted to the shelf 80 and to the other parts of the swing 34. Wires 106 lead from the motor 100 to a suitable source of electrical energy, not shown.

It is thus seen that there is provided apparatus for oscillating and vibrating a radiator or the like within a tank of chemical solution for cleaning out the radiator. By means of the vibrating and oscillating arrangement, it is possible to clean out a radiator more thoroughly and quickly than has heretofore been possible.

In the drawings and specification there has been set forth a preferred embodiment of the invention, and although specific terms are employed, they are used in a generic and descriptive sense only, and not for purposes of limitation, the scope of the invention being defined in the claims.

I claim:

1. Apparatus for cleaning radiators and the like comprising a tank adapted to contain a cleaning solution, means for heating the solution within said tank, support means connected to said tank and extending upwardly therefrom and having bearings in the upper end thereof, a swing oscillatably mounted in the bearings of said support means and extending downwardly within the confines of said tank, a platform secured on the lower portion of said swing, means for securing radiators to said platform, said bearings in the upper portions of said support means being so constructed as to permit said swing to oscillate therein and also to permit said swing to be removed from within the confines of said tank, driving means for imparting oscillatory movement to said swing, and additional driving means for vibrating said swing as it is oscillated in the solution in said tank.

2. Apparatus for cleaning radiators and the like comprising a tank adapted to contain a

cleaning solution, means for heating the solution within said tank, support means connected to said tank and extending upwardly therefrom, bearings mounted in the upper ends of the support means, an inverted U-shaped swing oscillatably mounted in the bearings of said support means and having arms extending downwardly within the confines of said tank, a platform connected to the lower ends of said arms and spanning the distance therebetween, means for securing a radiator to said platform, said bearings in the upper portions of said standard means being slotted to permit said swing to rotate therein and also to permit said swing to be removed from within the confines of said tank, driving means for imparting oscillatory movement to said swing, vibrating means for vibrating said swing as it is oscillated in the solution in said tank, and additional driving means for said vibrating means.

3. Apparatus for cleaning radiators and the like comprising a tank adapted to contain a cleaning solution, means for heating the solution within said tank, standard means connected to said tank and extending upwardly therefrom and having bearings in the upper end thereof, a swing oscillatably mounted in the bearings of said standard means and extending downwardly within the confines of said tank, a platform secured to the lower portion of said swing, means for securing a radiator to said platform, said bearings in the upper portions of said standard means being so constructed as to permit said swing to oscillate therein and also to permit said swing to be removed from within the confines of said tank, driving means for imparting oscillatory movement to said swing including a motor mounted on said standard and a link operatively connected to the motor and to the swing, and vibrating means for vibrating said swing as it is oscillated in the solution in said tank.

4. Apparatus for cleaning radiators and the like comprising a tank, a plurality of uprising beams secured to said tank, a swing oscillatably and removably mounted in said upstanding beams, a platform secured to the lower portion of said swing and being disposable within the confines of said tank, means on said platform for securing a radiator thereto, a first driving means mounted on one of said upstanding beams and connected to said swing for oscillating the same in said tank, and a second driving means carried by said swing and having off-center weight means associated therewith for setting up vibration of said swing whereby said tank may be filled with cleansing solution and a radiator to be cleaned may be positioned on the platform of said swing and may be oscillated within the tank and may also be vibrated during the cleaning process.

5. Apparatus for cleaning radiators and the like comprising a tank, a pair of uprising beams having their lower ends secured to said tank, the upper ends of said beams being bifurcated, an inverted U-shaped swing oscillatably and removably mounted in the bifurcated portions of said upstanding beams and having arms depending therefrom into said tank, a platform secured between the lower ends of said arms of said swing and being disposable within the confines of said tank, bolt means on said platform for securing radiators thereto, a first driving means mounted on one of said upstanding beams, one of said arms of said swing having a pin secured thereto, a link connected to said

first driving means, said link having a slot in one end thereof adapted to fit over said pin for removably connecting said link to said swing for oscillating the same in said tank, and a second driving means mounted on said swing and having off-center weight means associated therewith for vibrating said swing whereby said tank may be filled with cleansing solution and a radiator to be cleaned may be positioned on the platform of said swing and may be oscillated within the tank and may also be vibrated during the cleaning process.

6. Apparatus for cleaning radiators and the like comprising a tank adapted to contain a cleaning solution, uprising beams extending from said tank to a point substantially above said tank, the upper ends of said beams being bifurcated, a bearing positioned in the upper bifurcated portion of each of said beams, said bearings being slotted, a shaft oscillatably and removably mounted in said bearings, an inverted U-shaped swing fixed to said shaft and having arms depending between said uprising beams, the lower ends of said arms of said inverted U-shaped swing being disposed within the confines of said tank, a platform secured to the lower portion of the arms of said inverted U-shaped swing, means for securing a radiator to said platform, a motor platform secured to one of said upstanding beams, a motor mounted on said platform and means detachably connecting said motor to said inverted U-shaped swing for imparting oscillatory movement thereto, a shelf extending between the depending arms of said inverted U-shaped member and connected thereto above said platform, and a second motor mounted on said shelf and having vibrating means associated therewith for imparting vibration to said inverted U-shaped swing.

7. Apparatus for cleaning radiators and the like comprising a tank adapted to contain a cleaning solution, a pair of uprising beams extending from said tank to a point substantially above said tank, the upper ends of said beams being bifurcated, a spring pressed bearing positioned in the upper bifurcated portion of each of said beams, said bearings being slotted, a shaft extending between said beams and having its ends oscillatably and removably mounted in said slots in said bearings, an inverted U-shaped swing fixed at its upper end to said shaft and having arms depending between said uprising beams, the lower ends of said arms of said inverted U-shaped swing being disposed within the confines of said tank, a platform secured to the lower portion of the arms of said inverted U-shaped swing, bolt means for securing radiators to said platform, a motor platform secured to one of said upstanding beams, a motor mounted

on said platform, link means detachably connecting said motor with said inverted U-shaped swing for imparting oscillatory movement thereto, a shelf extending between the depending arms of said inverted U-shaped swing and connected thereto above said platform, a second motor mounted on said shelf, said second motor having a shaft extending therefrom, and at least one off-center weight mounted on said shaft causing said motor to vibrate to thus impart vibration to said inverted U-shaped swing.

8. Apparatus for cleaning radiators and the like comprising a tank adapted to contain a cleaning solution, means for heating the solution within said tank, a pair of uprising beams connected at their lower ends to said tank and extending upwardly from said tank to a point substantially above said tank, the upper ends of said beams being bifurcated, a spring pressed bearing positioned in the upper bifurcated portion of each of said beams, said bearings being slotted, a shaft, an inverted U-shaped swing comprising a web portion and depending arms, said shaft extending between and secured to said arms adjacent the web portion and penetrating said arms and extending outwardly therefrom, the opposite ends of said shaft being removably and oscillatably mounted in the slots of said bearings, the lower ends of said arms being disposed within the confines of said tank, a platform secured to the lower end of said arms, means for securing radiators to said platform, a motor platform, a motor mounted on said platform and means removably connecting said motor to one of said arms for imparting oscillatory movement to said U-shaped swing, a shelf extending between the depending arms and connected thereto above said platform, an inverted U-shaped motor platform secured to said shelf, a vibrating shaft mounted in said motor platform, an off-center weight mounted on said vibrating shaft, a second motor mounted on said shelf, and means connecting the second motor with said vibrating shaft for rotating the same to impart vibration to said inverted U-shaped swing.

DAVID JESSE LOGAN.
